DECORTICATING APPARATUS

Karl Kaiser, El Centro, Calif., assignor to California Central Fibre Corporation, a corporation of California

Application May 19, 1941, Serial No. 394,048

7 Claims. (Cl. 19—30)

My invention relates to decorticating apparatus and more particularly to a portable machine adaptable for decortication in the field of various fibers such as flax, ramie, hemp, jute, crotalaria and other bast fiber producing plants. The machine is described hereafter with particular reference to flax but it is to be understood that it may be adapted for use for various other fiber containing plant materials of similar physical properties.

For use in the manufacture of certain high quality paper from flax, such as for example cigarette paper, it is desired to treat the flax straw so as to liberate at least partially the bast fiber from the other components principally the woody center portion of the flax stalk commonly referred to as shive. Heretofore, it has been the common practice to transport the flax straw to a decorticating plant having a permanently installed machine line through which the straw is passed one or more times for decortication.

The prior attempts with portable decorticators have not proven commercially satisfactory principally because they did not effect sufficient separation of shive and cleaning of the bast fiber to make field decortication profitable. Also the machines were not adapted to multiple operation. The prior, field decorticated, fiber material still required about the same treatment in the permanent machine line as the regular untreated straw and therefore the expense of the preliminary field decortication could not be justified.

In accordance with my invention I have produced a portable decorticator that can be successfully operated in the field where the flax straw is cut. The satisfactory commercial operation of this machine is made possible by the efficient functioning of the machine in cleaning of the fiber. This operation is performed so efficiently that little or no subsequent treatment of the fiber in the permanent machine line will be required. In other words, the decorticating action of the machine removes the large proportion and in some cases all of the shive that is required to be removed to render the resulting fiber product suitable for use in the manufacture of high quality paper.

A commercial advantage of my machine is that flax areas which are isolated or have small acreages can be processed into finished fiber ready for use in the paper manufacture by treatment one or more times in the same machine or in multiple machines. Thus flax is made available which would be impractical of use under the conventional central plant plan of operation.

One of the principal reasons for the marked improvement in my machine as compared with the prior portable machines is the new combination of the several decorticating, cleaning, and condensing devices employed in my machine. These comprise generally a brake roll assembly, having a plurality of light weight, high spaced rolls, a conical cleaner or duster, and a fiber aggregator or condenser, all connected in sequential 5 cooperative relationship.

The light weight brake rolls operating at extraordinary high speeds produce a snap action on the flax stalks that is conducive to efficient separation and removal of shive. Such operation is substantially superior to the conventional, relatively slow speed rotation of heavy solid brake rolls. The light weight rolls have also made possible the use of a larger number of brake rolls without unduly increasing the total weight of the 10 portable machine.

The partially decorticated fiber delivered by the improved brake roll assembly, even though markedly better than the usual fiber produced by the same number of slower operating prior art rolls, 15 is not sufficiently free of shive to be acceptable for high quality paper manufacture. Accordingly, in my improved machine I have provided a new form of fiber cleaner that receives the flax material from the brake roll assembly and operates on it 20 in such a manner that the mass of material is loosened, bloomed and thinned and large portions of the remaining shive efficiently removed from the fiber. This operation is performed in my conical cleaner without any substantial cutting, 25 scutching, hackling or carding action. Thereby 30 injury to and shortening of the desired bast fiber is avoided and a high quality product produced.

When the straw has been broken and cleaned 35 as described, it is collected and concurrently further cleaned or refined by my condenser apparatus which is operatively connected to the delivery end of the conical cleaner. The condenser collects or aggregates the fiber and delivers it in a form and quantity suitable for direct baling or 40 for delivery to another machine where complete refining of the fiber is to be accomplished in the field. The condenser is so constructed and operated as described hereafter that it effects further removal of shive and dust concurrently with 45 collection of the fiber and thereby cooperates with the conical cleaner and brake assembly to produce clean fiber. Prior portable machines made no provision for collecting and cleaning fiber with a condenser. Such machines suffer a loss of fiber 50 by reason of blowing fiber away with the shive.

Also, their deficiency in collection of fiber prevents multiple operation of machines.

For the manufacture of high quality paper it is desirable to remove a preponderant portion of the shive component of the straw. I have found that my machine, employing the above described improvements, will largely accomplish the necessary removal of the shive upon passing of the straw once through the machine. To remove the remaining small percentage of shive the straw may be passed through the machine a second time or through a similar machine operating in tandem, or may be given some slight decortication treatment in the machine line at the permanent plant preliminarily to introduction of the fiber into the pulping and paper making process.

In a number of instances the paper quality requirements are not as rigid as the exceptional one described above and the removal of shive, resulting from one pass of the straw through the machine, would suffice. Accordingly the fiber thus produced could be baled directly and shipped to the paper factory without further decortication.

The power for operating my decorticator machine may be supplied by a tractor or any other suitable power means connected to the decorticator or alternatively, an engine or motor may be installed directly on the decorticator frame.

The construction and mode of operation of the machine of my invention will be more fully understood from the following detailed description taken in conjunction with the accompanying drawings, in which like reference characters identify similar parts and in which:

Fig. 1 is a view of one side of the machine;

Fig. 2 is a view of the other side of the machine;

Fig. 3 is a plan view of the machine with some parts removed for sake of clarity;

Fig. 4 is an end view of the machine;

Fig. 5 is an enlarged longitudinal sectional view of a portion of the fiber cleaning equipment on the machine;

Fig. 6 is a detail of the end brake rolls and associated parts, shown in Fig. 5;

Fig. 7 is a cross-sectional view of the fiber conveyor and housing;

Fig. 8 is a cross-sectional view of the fiber conveyor;

Fig. 9 is a plan view partly broken away of two of the hollow brake rolls and supports therefor.

Fig. 9A is a detail of the two rolls shown in Fig. 9;

Fig. 10 is a front elevational view of a brake roll bearing assembly;

Fig. 10A is a detail of a top roll spring;

Fig. 11 is a diagram of the drives used on the decorticator machine;

Figs. 12, 12A and 12B are diagrammatic showings, partly in section, of the drives for the smooth end rolls of the brake roll assembly;

Fig. 13 is a diagrammatic representation of the complete straw treating system, and

Fig. 14 is a diagrammatic showing of a modified arrangement of the straw treating system.

Referring now to the several figures in the drawings and generally in the order in which they occur, my portable decorticator comprises generally, a feed hopper 10 for receiving the flax straw; straw walkers 11; a feeding device indicated generally at 12, which regulates the amount of straw passing through the machine; a brake roll assembly 13; a fiber transfer device 14; a conical cleaner 15 and a fiber condenser 16. These prin-

cipal parts of the apparatus are supplemented by various detail constructions which are described hereafter, but they represent, generally speaking, the main operative parts of the equipment. The portable machine has a lower frame 17 and a substantially parallel upper frame 18; wheels 19 for easy transportation of the machine, and a fifth wheel 20 which is capable of turning 180°. The upper and lower frames of the machine are connected by gusset plates 21.

Considering now the more detailed parts and operation of the machine, the flax or other straw is conveyed up the conveyor 22. This straw conveyor is detachable from the machine and during operation is connected to the brake feed hopper 10. This detachable straw conveyor may be either a slat conveyor or a flat belt conveyor or any other suitable type of conveyor. The conveyor may be located in line with the portable machine for stationary feeding of the flax, such as for example, from a nearby stack of flax straw. Alternatively, the conveyor may be offset to one side to permit the tractor connection, described hereafter, and feeding of the straw while the portable brake is moving. In such a case wheels may be provided at the lower end of the conveyor and a cross-conveyor may also be provided between the upper end of this straw conveyor 22 and the brake feed hopper 10. These alternative arrangements will be easily understood by one skilled in the art and do not require additional illustrations to those shown herein and described more in detail hereafter.

The straw from the conveyor 22 is dropped into the hopper 10 which may be of conventional construction comprising angle iron frame and sheet metal sides. The straw is deposited on the straw walkers 11, four of which are shown in Figure 3. These walkers are constructed of channel supports 23 covered with sheet metal slats of triangular cross-section indicated at 24. The walkers are provided with a shaft 25 and eccentrics 26. Operation of the shaft with these eccentrics produces an up-and-down motion and concurrently a generally forward motion of straw walkers 11 which carries the straw into the field of operation of the feeding drum described below. The straw walkers are also provided with rocker arms 27 which function to pivot the straw walkers at the end opposite to the eccentrics 26. Underneath the straw walkers is located a dust or chaff guide 28 which conveys the chaff and dust from the straw towards the drag chain 60 described below.

In the feeder generally indicated at 12, the straw first comes into contact with the large diameter feed drum 29 having angularly set teeth 30 and rotating in the direction indicated by the arrow. The drum may be of any conventional suitable construction such as wooden staves having the pins 30 driven therethrough and extending about one to two inches beyond the wood at an angle of about 45°.

Rotation of the drum causes varying amounts of the straw to be carried up and around the periphery of the drum until it comes into contact with a doffer cylinder 31. This doffer cylinder may be of any suitable construction such as for example, separated metal discs having tubular pin bars 32 spaced around the periphery of the doffer cylinder. The bars 32 may be held by U-clamps, not shown, or by other suitable means. This doffer cylinder upon rotation in the direction indicated by the arrow knocks off excess amounts of straw carried by the feed drum 29

and thereby permits only a certain amount of straw to be transferred to the stripper drum 33.

The doffer cylinder 31 in combing off the excess straw from the feed drum permits only a certain thickness of the straw to pass. This combing action is effected by means of the tubular pin bars, six such bars being used in practice for efficient operation. The angle at which the tubular pin bars are set governs the line of throw-off of the straw. This doffer drum 31 is supported on slidable bearings (not shown) in order to regulate the gap between the doffer and the feed drum.

The stripper drum 33 rotating in a direction opposite to that of the feed drum 29 causes the straw carried by the feed drum to be stripped therefrom. This stripping action is produced by the tubular pin bars 34 on the drum 33 passing between the teeth 30 of the feed drum 29.

The straw feeder which is comprised generally of the feed drum 29, the doffer drum 31 and stripper drum 33 cooperating as above described, has a housing 35 which substantially covers these drums. A portion 36 of the housing adjacent the stripper drum 33 is hinged as shown at 37. The purpose of this is to provide easy access to the feeder and to permit removal of straw if it becomes wound around the stripper drum.

The straw, stripped from the feed drum as described above, falls onto a chute or conveyor 38 for delivery to the brake roll assembly indicated generally at 13. This brake roll assembly comprises a series of fluted bottom rolls 39 and a corresponding series of fluted top rolls 40. The bottom rolls are driven by positive drives as described hereafter and since they mesh with the top rolls they cause corresponding rotation of the top rolls. The brake rolls are mounted in bearings which are positioned by short brake pins 41 and long brake pins 42, and the top rolls are resiliently held by springs 43.

The last two rolls in the brake roll assembly, namely, top roll 44 and bottom roll 45 are smooth surface rolls for the purposes described hereafter. The other rolls in the brake assembly are corrugated or fluted rolls and may have the same or different number of corrugations or flutings on the successive rolls in the assembly.

The straw, as it passes between the several sets of brake rolls shown in the assembly 13, is subjected to the braking and compressing action of the rolls as they rotate at high speed. The result is that a substantial amount of the woody component of the straw, called shive, is separated from the outer bast fiber of the straw and falls down through spaces between the rolls and is carried away by the drag chain 60 described below.

The broken and partially decorticated material delivered by the smooth rolls 44 and 45 comes in contact with the endless belt or chain transfer device 46. This transfer device carries the material up the incline shown, within the conveyor housing 46A and delivers the straw material into the square intake duct 47 located at the top of the conical cleaner 15.

Within the conical cleaner 15 the partially decorticated fiber is further cleaned and freed of shive by the operation of the rotor elements shown in Figure 5 and described more in detail hereafter. The rotary elements in the conical cleaner cause the fiber to be conveyed from the small end of the cleaner, where it enters, to the large end of the cleaner. This cleaner has a conically shaped outer covering generally indi-

cated at 48. The shive that is freed from the fiber in the conical cleaner falls through the reticulated bottom of the cleaner housing as shown and described later in connection with Fig. 5. Guide shields for this shive which extend along the lower edge of the screen frame parallel with the shive conveyor are shown at 49 in Fig. 4.

The fiber thus cleaned by the action of the conical cleaner is removed from the bottom of the cleaner at the large end thereof by means of a duct or conduit 51 and is transferred by suction upward through this duct to the fiber condenser 16. This condenser is supported by the condenser frame 52.

The condenser 16 operates as above suggested to concentrate the fiber drawn through the duct 51 to the condenser by suction and further to separate out the shive and dust. The separated shive is removed by suction through conduit 53.

The cleaned fiber falls from the condenser onto a fiber delivery chute 54 and from thence onto a fiber conveyor 55. This conveyor may carry the fiber to a baler or to additional decortinating equipment, such as a duplication of the machine shown in Figs. 1 to 4, for further decortication and refinement. In view of the fact that the fiber condenser is located in line and at the rear of the conical cleaner the cleaned fiber output of the condenser may be easily transferred to a second decortinating machine connected in tandem with the machine shown in the drawings. This transfer may be made either directly to the brake rolls of the second machine by means of the chute 54 or by the conveyor 55, arranged in line with the machine, to the feeder of the second machine.

The suction for conveying the fiber and shive through the conduit 51 and the removal of the shive only through the conduit 53 is applied by a fan indicated at 56. This fan is also connected to duct 57 for removal of the shive separated in the brake roll assembly and conical cleaner and which falls onto the shive drag chain 60 operating over sprockets 59. The delivery side of this fan is connected to conduit 58, which in practice may extend for a number of feet upward and outward from the machine and through which the shive may be blown by the fan 56 to a convenient location away from the machine.

To complete the general description of the machine shown in Figs. 1 to 4, brief reference is made here and given more in detail hereafter, to the brake roll driving mechanisms shown in these first figures. They include jack shafts and sprockets such as indicated generally at 61 and 63 in Fig. 1 and roller chains such as shown generally at 62 and 64. The arrangement is such that odd numbers of brake rolls, i. e. one, three, five, etc. are driven by the sprockets 63 and roller chains 64 located on one side of the machine as shown in Fig. 2; and the even numbers of brake rolls, i. e. two, four, six, etc. are driven by the corresponding elements 61 and 62 located on the opposite side of the machine as shown in Fig. 1. Further details of the drive are discussed hereafter in connection with Fig. 11.

Referring to Fig. 4 which is a rear end view of the machine the large end of the conical cleaner is indicated generally at 48 and the shive guide shields at 49. The shive removal conduit 53 is formed in a more or less substantially U-shape and as above indicated connects with the fiber condenser 16 on one end and the shive blower or fan 56 on the other end. The fiber duct 51, which conveys the fiber from the conical cleaner to the

condenser, extends outward and upward from the conical cleaner and enters the condenser on a plane substantially parallel with the machine. The supporting condenser frame is indicated at 52 and the condenser cleaning roll is shown at 58.

Referring now to Fig. 5 which shows in greater detail certain of the improved features of my decorticating machine, these features are considered further as they appear from left to right in the drawings. The two smooth-surface delivery rolls 44 and 45, as shown, are the last two rolls in the brake assembly indicated generally at 13. These rolls, are similar to the other brake rolls 39 and 40 except that they do not have flutings on their surfaces, that is, they are not corrugated. The purpose of these smooth delivery rolls is to provide more efficient transfer of the fiber from the corrugated brake roll set to the fiber conveyor 46. The combination of these smooth surface rolls together with the cooperating scraper blades, about to be described, effects good delivery of the fiber to the fiber conveyor and prevents winding of the fiber around the last two rolls in the brake roll set as otherwise commonly occurs.

Arranged substantially tangentially to the surface of the smooth rolls 44 and 45 are two scraper blades 65 and 66, the details of which are more clearly shown in Fig. 6. These scraper blades are mounted on square pivot shafts 67. The bearings 68 for upper pivot shaft 67 are mounted on the bearing 109 for the smooth top roll 44 so that the scraper blade 65 will follow the lifting movement of the smooth top roll 44 and maintain contact therewith at all times. Each of the scraper blades is made of spring steel, which I have found offers substantial advantages, and has a flat steel backing 69 and a flat steel cover 70. The spring steel of the scraper blade has, advantageously, a thickness of about 0.010 inch to 0.020 inch. It is to be noted that the flat steel cover 70 is beveled to facilitate free fiber flow.

To provide for desired movement of the scraper blades a lever 71 is fastened to each pivot shaft 67 and a tension spring 72 is connected at the other end of the lever 71. It is to be noted that the bearing 68 for the lower pivot shaft 67 is mounted on the upper trailer frame 18. Under the tension applied by the springs 72, the scraper blades 65 and 66 contact the surface of the two smooth rolls and remove therefrom any fiber which tends to pass around these rolls during operation of the machine.

Located adjacent the smooth rolls 44 and 45, above described, is the fiber conveyor 46. This conveyor may assume several forms but is shown in Fig. 5, and more in detail in Figs. 7 and 8, as a slat conveyor built on a roller chain with attachments. This conveyor comprises several special features including the following: It operates at relatively high speed, that is, at the brake roll surface speed and therefore accommodates the fiber supplied by the brake rolls without backing-up of the fiber delivered from the brake rolls. Flat steel connectors are provided between the slat and chain attachments; and a housing with narrow slits in which the steel connections travel, are provided to prevent the fiber from winding in the roller chain. These and other elements of the conveyor are shown in Figs. 5, 7 and 8 and identified as follows:

The lower conveyor shaft with take-up bearings is shown at 73 and 74, respectively. A roller chain sprocket 75 is mounted on each end of this

shaft for moving and guiding the roller chain with attachments 76. A relatively large diameter smooth roll 77 is provided on the shaft 73 to prevent the fiber from winding around this shaft. The roller chain 76 carries at spaced intervals wooden slats 78 and the chain rides on steel rails 79. This fiber conveyor is equipped with a sheet steel flooring 80 and also with a return metal shield 81, for carrying the shive to the blower drop. The conveyor is supported by a structural steel frame 82 and covered with a housing 48A.

At the upper end of the fiber conveyor there is provided a duplicate shaft, smooth roll, and sprocket combination described below for guiding and returning the conveyor chain 76. The housing for this portion of the conveyor is curved as shown at 83 for conducting the mass of fiber and some shive, carried by the conveyor, downward into the opening indicated at 84 in the small end of the conical cleaner 15.

Referring now to some of the details of the conical cleaner, the small end thereof has a cover plate 85 and the large end thereof has a cover plate 86. The housing portion of the conical cleaner is held together by longitudinally arranged tie rods 87 as shown in Fig. 2. The bottom portion of the conical cleaner is made of an open mesh screen 88 supported by a screen frame 89. The shive that is liberated from the fiber by the action of the conical cleaner passes through the openings in the screen member 88 and falls onto the shive drag chain 60.

Extending longitudinally through the center of the conical cleaner is a large diameter rotor 90 which supports a plurality of flat rotor blades 91 somewhat spirally arranged around the rotor. These blades are shown as flat blades without pitch, however, some or all of the blades may be twisted if desired to speed the travel of the fiber through the conical cleaner. These blades 91 have generally, smooth, dull ends and edges and since they do not coat with any fiber holding elements in the conical cleaner (such as commonly used in scutching or hackling machines) no appreciable scutching or hackling takes place in this conical cleaner. The primary purpose of the blades is to loosen the fiber, that is, to make the fiber "bloom" and thereby effect separation of the included or entangled shive. The beating action of the blades loosens the shive from the fiber so that a substantial further separation and disposal of shive is obtained.

The cleaned fiber produced in this conical cleaner is drawn through the conduit 51 from the large end of the cleaner and conducted through the conduit up to the condenser 16 in the manner already described before. The upper portion of the conduit 51 is formed into a substantially flat, spreader pipe section 92. This spreader pipe 92 is connected at the junction 93 with the condenser entrance 94. The condenser comprises a rotating outer perforated cylinder 95 and a stationary internal suction head 96 which is connected with the suction fan described hereinabove. The effective segment of the suction head is indicated at 97, where the solid metal surface of the suction head is omitted, so that the shive and waste portions of the fiber are permitted to enter the perforations 98 and pass into the shive conveying duct 53.

The long bast fiber now cleaned from the major portion of the shive is aggregated, collected or condensed on the confined circumferential surface of the outer perforated cylinder 95 where

it covers the open portion of the suction head and is thence passed between the outer cylinder 95 and a roll 99. This roll is a rubber covered fiber discharge roll, preferably made of synthetic rubber, and acts as a seal for the suction on the suction head of the condenser while the fiber is rolled out therefrom. The fiber thus transferred falls onto the discharge shield 54 and slides down this shield onto a belt or other conveyor 55 which leads to either the baling chamber of a fiber baling press or to another decorticating machine as described before. A bladed combing roll 158 is located adjacent the lower surface of the perforated cylinder 95 and rotates to keep the perforated cylinder clean.

The shive which is produced in the above described operation of the machine is transferred to the lower part of the machine and from there out to the ground as already referred to above. The several parts of the apparatus employed for this shive disposal are identified more in detail as follows:

A small portion of shive, and principally the chaff and dust originally present in the straw as it is fed to the machine, falls down through the spaces between the straw walkers 11 shown in Figs. 1 to 3 and is collected in the sheet metal pouches 28 located underneath the straw walkers. The shive, chaff and dust in the pouches 28 is conveyed to the shive drag chain 60 located beneath the brake roll assembly. The shive drag chain arrangement beneath the conical cleaner, as shown in Fig. 5, has on each end a pair of sprockets 59. Between the sprockets is provided a sheet metal cylinder 100 for guiding the shive. Each sprocket shaft is equipped with such a cylinder. The drive shaft which rotates the sprocket 59 is shown at 101. The wooden slats which are located at spaced intervals in the drag chain 60 are shown at 102. A sheet metal flooring 103 is located beneath the shive drag chain 60. To prevent the lower shive drag chain from sagging, tracks 104 are provided. By movement of the drag chain 60 carrying the slats 102, the shive which is separated in the conical cleaner 15 is dragged to a point adjacent the end of the brake roll assembly and as the drag chain passes over the sprocket 59 the shive is dumped into a shive drop 105 which in turn is connected to suction pipe 57. The latter is connected to suction fan 56. The blast side of this fan is connected to the shive disposal pipe 58 that extends outward and away from the machine for blowing the shive away from the machine as already described above.

Beneath the brake roll assembly 13 there is provided a shive disposal drag chain arrangement which is the substantial duplicate of the arrangement described just above in connection with the conical cleaner and for practical purposes may be considered the same in structure and operation. Like reference characters have been applied to parts of this brake roll assembly shive disposal arrangement which correspond to those for the conical cleaner shive disposal. The shive removed by the drag chain operating under the brake roll assembly is transferred to the same shive drop 105 and is removed therefrom as already described.

Referring next to Figs. 9, 9A, 10 and 10A, some of the details of the brake rolls and associated parts, are shown therein. Each of the top rolls 40 and bottom rolls 39, has a hollow cast iron shell 106 having cast teeth or flutes 107, and a center shaft 108.

Each roll shaft 108 is supported on each end by

5 non-friction ball bearings indicated generally at 109 for the top roll and 110 for the bottom roll, and is fastened to the outer hollow shell 106 by means of the bushings 112 and 113 described below.

To provide efficient transmission of torque between the shaft 108 and the shell 106 I employ a flange bushing 112 adjacent the ball bearings 109 and extending into the shell 106 up to the point 10 of the increased bore diameter indicated at 111. At the opposite end of the roll I have provided a tapered bushing 113 which serves to maintain tight connection between the shaft 108 and the shell 106, thus preventing rattling or other adverse effects of loose connections.

15 The hollow type rolls shown in Figs. 9 and 9A and described just above, are substantially lighter in weight than the conventional solid rolls and therefore are operable at very much higher speeds. The use of the ball bearings 109 and 110 also accelerate the operation speed. The cast teeth 107 do not require machining and the hard cast skin surface is more wear resistant than that of machined teeth. In the event the teeth become damaged, the shell 106 may be removed and the same shaft 108 used over again, thereby materially reducing the usual replacement costs for solid machined rolls.

20 In Figs. 10 and 10A, there is shown in front elevation, a unit of the brake roll assembly. It comprises the short brake pins 41 and long brake pins 42, respectively, for holding the bottom rolls against lateral displacement and for permitting the top rolls to move vertically. The top rolls are 25 connected together in pairs by means of a saddle shown at 114 which rests on the top roll bearings 109, and which is held under tension of the helical spring 43. The bottom rolls are rotatively supported in bearings 110.

30 The various drives for the decorticating machinery described above are shown generally in Fig. 11 and the driving connections between the portable machine and the sources of power are indicated schematically in Figs. 13 and 14. Referring now to these figures and generally in the order in which they occur, the system shown in 35 Fig. 11 derives its power through the intermediary of the belt 115. This belt may be connected on the other end to a tractor power take off as shown in Fig. 13 or to an engine mounted on the end of the portable decorticator as shown in Fig. 14.

40 The belt 115 drives the main drive pulley 116, shown in Fig. 1, which is mounted on the main cross shaft 117. A jack shaft 118, which is 45 mounted above the conical cleaner 15, is connected to the main shaft 117 by means of a chain or belt drive indicated at 119. A chain drive 120 conveys power from the shaft 118 to the shaft 121 of the condenser combing roll 158, shown in 50 Fig. 4.

55 A V belt drive 122 connects the main cross shaft 117 to a pulley 123 mounted on the shaft 124 of the fan 56, shown in Fig. 4, and thereby conveys operating power to the fan.

60 The shafts 101 are the drive shafts for the shive conveyor located underneath the brake rolls and conical cleaner, as shown in Fig. 5. They obtain their rotating power through sprocket 138 and chain drive 125, which is connected to sprocket 130 on the jack shaft 126 and the latter in turn connected to the shaft 127. The sprocket 128, which is mounted on the shaft 127, drives chain 129 which effects rotation of the ninth and eleventh bottom rolls, shown in Fig. 2. The sprocket 130, on shaft 126, drives

chain 131 and thereby rotates the thirteenth and fifteenth brake rolls, shown in Fig. 2.

Mounted on shaft 117 is a right angle gear drive 132 and connecting the latter with the conical cleaner rotor 90 is a V belt drive 133, as shown in Figs. 2 and 5. Connecting the shafts 117 and 127 is a chain drive 134 operating over a large sprocket 135 on shaft 127. On the opposite end of shaft 127 is sprocket 137 which drives chain 138 and the latter effects rotation of the tenth and twelfth brake rolls as shown in Fig. 1.

A chain drive 139 connects shaft 127 with shaft 140, and a sprocket 141 thereon drives chain 142 and thereby the fifth and seventh brake rolls shown in Fig. 2. On the other end of shaft 140 is sprocket 143 and chain 144 which drive the sixth and eighth brake rolls, shown in Fig. 1.

Connecting shaft 140 with the next jack shaft 145 is a chain drive 146. On shaft 145 is mounted sprocket 63 carrying chain 64, as shown in Fig. 2, which drives the first and third brake rolls, as previously referred to. On the other end of shaft 145 is sprocket 61 and chain 62 that effect rotation of the second and fourth brake rolls, shown in Fig. 1.

On shaft 127, adjacent sprocket 137, is a large pulley 147 that connects by means of a crossed flat belt 148 to pulley 149 on shaft 150 of the stripper drum 33, shown in Fig. 1. The stripper shaft 150 is connected to the shaft 151 of the doffer drum 31, by means of a crossed flat belt drive 152. The stripper shaft 150 is also connected to the eccentric shaft 25 by means of a crossed flat belt 153.

The eccentric shaft 25 is provided with a clutch 154, and a chain drive 155 which connects shaft 25 with the shaft 156 of the feed drum 29. A chain drive 157 connects the eccentric shaft 25 with the shaft on the straw conveyor 22, shown in Fig. 1.

Referring to Figs. 12, 12A and 12B there is shown generally an arrangement for providing a positive drive to the two smooth end rolls 44 and 45. The bottom roll 45 is driven from the same jack shaft 126 that drives the fourteenth brake roll. The chain 159, shown in Fig. 1, is connected to this jack shaft 126 and thereby effects rotation of the bottom smooth roll 45 and the fourteenth fluted bottom brake roll.

The top smooth end roll is driven by means of the following arrangement; a gear 160 is connected to the shaft of the thirteenth, bottom, fluted roll and this gear meshes with a gear 161 which in turn carries a sprocket 162. A similar sprocket 163 is mounted on the shaft of the smooth top delivery roll 44. These two sprockets 162 and 163 are connected by a chain drive 164. In this manner the thirteenth, bottom, fluted roll, which is driven by sprocket 130 and chain 131 as described above, provides a positive drive for the smooth top roll 44.

Referring now more in detail to Figs. 13 and 14, the arrangement shown in Fig. 13 is used where the portable decorticator does not supply its own operating power but obtains the same from a tractor or other suitable power supply connected by the belt shown at 115. In such case the conveyor for transferring the fiber from the portable decorticator to the baler is arranged transversely to the decorticator so as not to interfere with the power supply.

In the arrangement shown in Fig. 14 two portable decorticators are connected in tandem and

are spaced apart a short distance by a fiber conveyor which transfers the partially decorticated fiber produced by the first machine, to the second decortinating machine that completes the required separation of shive from the bast fiber. The clean fiber delivered from the second machine is baled as indicated and is ready for shipment to the paper factory. In the arrangement of Fig. 14, the operating power for both machines is obtained as indicated from the engine mounted at the rear of the first portable decorticator.

Various modifications and changes may be made in the constructions and methods of operation described hereinabove without departing from the purview of my invention, some of the novel features of which are defined in the appended claims.

The hollow brake rolls and method of manufacture referred to above and illustrated in part in the drawings are not claimed in the present application but are fully disclosed and claimed in my copending application Serial No. 645,840, filed February 6, 1946.

I claim:

1. In straw decortinating apparatus having means for breaking the straw to loosen the flexible bast fiber from the shive normally combined therewith and thereby produce a heterogenous mixture of bast fiber and loosened shive an horizontal cleaner and transfer means for transferring freely and loosely said mixture to said cleaner without scutching or cutting of the bast fiber, said cleaner being adapted for tumbling and separating said mixture of bast fiber and shive so that the shive can be discharged to waste and the bast fiber collected for use, said cleaner comprising a conical housing having smooth inner walls free of fiber scutching elements and a reticulated bottom for discharge of said shive, a rotor extending centrally and longitudinally through said housing, a plurality of separate, elongated, blades mounted on said rotor from one end to the other at relatively widely spaced locations and extending in close proximity to the inner walls of said housing but without contact therewith, said blades having generally smooth, dull edges and ends and upon rotation serve to bloom or disentangle the mixture of bast fiber and shive so that the shive is separated out through said reticulated bottom of said housing and the bast fiber is liberated without cutting or scutching and may be removed from the housing and collected for use.

55. 2. In straw decortinating apparatus having

roll means for breaking the straw to loosen the flexible bast fiber from the shive normally combined therewith and thereby produce a heterogenous mixture of bast fiber and loosened shive, an horizontal cleaner for tumbling and separating said mixture of bast fiber and shive so that the shive can be discharged to waste and the bast fiber collected for use, said cleaner comprising a conical housing having smooth inner walls free of fiber scutching elements and a reticulated bottom for discharge of said shive, a rotor extending centrally and longitudinally through said housing and located transversely to the axis of said roll means, a plurality of separate, elongated, flat blades mounted on said rotor from one end to the other at relatively widely spaced locations and extending in close proximity to the inner walls of said housing but without contact therewith, said blades having generally smooth, dull edges and ends and upon rotation serve to

bloom or disentangle the mixture of bast fiber and shive so that the shive is separated out through said reticulated bottom of said housing and the bast fiber is liberated without cutting or scutching and may be removed from the housing and collected for use.

3. In straw decorticating apparatus having means for breaking the straw to loosen the flexible bast fiber from the shive normally combined therewith and thereby produce a heterogenous mixture of bast fiber and loosened shive, an horizontal cleaner and transfer means for transferring freely and loosely said mixture to said cleaner without scutching or cutting of the bast fiber, said cleaner being adapted for tumbling and separating said mixture of bast fiber and shive so that the shive can be discharged to waste and the bast fiber collected for use, said cleaner comprising a conical housing having smooth inner walls free of fiber scutching elements and a reticulated bottom for discharge of said shive, a rotor extending centrally and longitudinally through said housing, a plurality of separate, elongated, twisted blades mounted on said rotor from one end to the other at relatively widely spaced locations and extending in close proximity to the inner walls of said housing but without contact therewith, said blades having generally smooth, dull edges and ends and upon rotation serve to bloom or disentangle the mixture of bast fiber and shive so that the shive is separated out through said reticulated bottom of said housing and the bast fiber is liberated without cutting or scutching and is propelled by said rotating, twisted blades through the length of said housing for collection at the exit end thereof.

4. In straw decorticating apparatus having means for breaking the straw to loosen the flexible bast fiber from the shive normally combined therewith and thereby produce a heterogenous mixture of bast fiber and loosened shive, an horizontal cleaner and transfer means for transferring freely and loosely said mixture to said cleaner without scutching or cutting of the bast fiber, said cleaner being adapted for tumbling and separating said mixture of bast fiber and shive so that the shive can be discharged to waste and the bast fiber collected for use, said cleaner comprising a conical housing having smooth inner walls free of fiber scutching elements and a reticulated bottom for discharge of said shive, a rotor extending centrally and longitudinally through said housing, a plurality of separate, elongated, blades mounted on said rotor from one end to the other at relatively widely spaced locations and being of progressively increasing length from the small end to the large end of said conical housing so that each of said blades extends to approximately the same distance from the adjacent inner wall of the housing but without contact therewith, said blades having generally smooth, dull edges and ends and upon rotation serve to bloom or disentangle the mixture of bast fiber and shive so that the shive is separated out through said reticulated bottom of said housing and the bast fiber is liberated without cutting or scutching and may be removed from the housing and collected for use.

5. In straw decorticating apparatus the combination of means for breaking the straw so as to loosen the shive from the bast fiber, and

means for receiving this broken straw in the form of a tangled mass and for tumbling and beating this mass to open it up and separate the previously loosened shive from the bast fiber so that the shive may be discharged to waste and the bast fiber reclaimed for further use, said receiving means being located in spaced relationship with said straw breaking means, and transfer means spanning the space therebetween for transferring said mass of broken straw from the breaking means to said receiving means, said transfer means being so constructed and arranged with respect to said receiving means that it delivers thereto said mass of broken straw freely and loosely and thereby avoids cutting and scutching of the straw, said receiving means comprising a cleaner having a housing with smooth interior walls, a rotor extending longitudinally through the center of said housing and non-cutting, non-scutching blades mounted on said rotor at relatively widely spaced locations and operative upon rotation to disentangle the aforesaid mass of broken straw and separate out the shive without substantial scutching or cutting of the bast fiber.

6. In straw decorticating apparatus the combination of means for breaking the straw so as to loosen the shive from the bast fiber, and means for receiving this broken straw in the form of a tangled mass and for tumbling and beating this mass to open it up and separate the previously loosened shive from the bast fiber so that the shive may be discharged to waste and the bast fiber reclaimed for further use, said receiving means being located in spaced relationship with said straw breaking means, and transfer means spanning the space therebetween for transferring said mass of broken straw from the breaking means to said receiving means, said transfer means being so constructed and arranged with respect to said receiving means that it delivers thereto said mass of broken straw freely and loosely and thereby avoids cutting and scutching of the straw, said receiving means comprising a conical cleaner having a housing with smooth interior walls, a rotor extending longitudinally through the center of said housing, and non-cutting, non-scutching blades mounted on said rotor at relatively widely spaced locations and operative upon rotation to disentangle the aforesaid mass of broken straw and separate out the shive without substantial scutching or cutting of the bast fiber.

7. An apparatus for decorticating straw, comprising means for feeding the whole straw, means for breaking the shive component of the straw to permit separation thereof from the bast fiber component, means for transferring said broken straw, and a cleaner located in spaced relationship to said transfer means for receiving and cleaning said broken straw, said transfer means effecting transfer of the broken straw to said cleaner loosely and freely so as to avoid scutching and tearing of the bast fiber, and said cleaner comprising means for tumbling and beating the broken straw to open it up and effect separation of the shive from the bast fiber, and said cleaner having means for moving said bast fiber through the cleaner without scutching or tearing of the fiber and thereby delivering from the cleaner a high yield of non-scuched fiber.

KARL KAISER.
